HULL CONSTRUCTION

Isidore Zuckermann, New York, N. Y.

Application July 8, 1940, Serial No. 344,445

2 Claims. (Cl. 114—9)

My invention relates to new and useful improvements in ship hull constructions.

An important object of my invention is to provide a ship's hull which may be adapted to men-of-war or other large seagoing vessels and which includes a protective jacket or armor uniquely adapted to resist torpedoes, submarine mines, storms, collisions, and explosions which will render the ship substantially unsinkable.

Another object of my invention is to provide a hull construction of the above-mentioned character which includes provision for rendering the same buoyant even though the hull should be pierced by a torpedo, or the like, below the water line.

Still another object of my invention is to provide a hull construction which is not only buoyant but which is strong and durable to withstand the buffettings of storms and heavy seas encountered by all seagoing vessels.

Other objects and advantages of my invention, will be apparent during the course of the following description.

In the drawings, forming a part of this specification, and wherein like numerals are employed to designate like parts throughout the same,

Figure 1 is a side elevation of a ship constructed in accordance with my invention.

Figure 2 is a vertical sectional view taken on the line 2—2 of Figure 1.

Figure 3 is a fragmentary longitudinal sectional view taken on the line 3—3 of Figure 2.

Figure 4 is a side elevation, showing parts in section, of an inflatable rubber tube comprising a part of my invention.

Figure 5 is a perspective view, showing parts broken away, of a pontoon comprising a part of my invention.

Figure 6 is a fragmentary transverse sectional view taken on the line 6—6 of Figure 5, and

Figure 7 is an enlarged fragmentary transverse sectional view of a hull embodying my invention.

In the accompanying drawings, wherein for the purpose of illustration, is shown a preferred embodiment of my invention, the numeral 10 designates a ship of the large seagoing type. The hull 11 of the ship is made of steel and is of conventional shape and construction. For the purpose of the present invention the hull is formed of steel plates of a thickness best determined by the size and type of vessel. In cross-section, the hull includes vertical side walls 12 and 13 the lower edges of which are rounded, as at 14, and connected by a substantially flat 55

bottom portion 15. The side walls of the hull extend substantially above the water line, designated by the numeral 16, and the upper edges thereof are connected by a transverse top 17.

5 In order that the hull may have a maximum of protection from torpedoes, collisions, explosions, storms, mines, gun fire, and the like, I have covered the same with a plurality of laminated or superimposed layers of various unique materials which serve as a shield or armor. The outer surface of the hull is first covered with a layer of cork 18 which may be from one to several inches thick. As best illustrated in Figure 7, the layer of cork extends upwardly along the 10 side walls 12 and 13 of the hull to a distance substantially above the water line 16. I have here illustrated the same as terminating flush with the lower deck of the ship. The layer of cork 18 is enclosed by a superimposed essentially thicker 15 layer of hard rubber 19, which layer 19 extends the same distance above the water line as the cork layer 18.

A plurality of steel beams 20 extend transversely of the hull in laterally spaced relation 20 with each other and at a height substantially equal to the top edges of the cork and rubber layers 18 and 19. The central portion of the beams extend between the side walls 12 and 13 of the hull and the ends thereof extend beyond 25 the side walls to support the pontoons 21.

All of the pontoons are identical in their construction and a detailed description of but one is, therefore, thought to be sufficient. As best illustrated in Figure 5, the pontoon comprises a

30 box-like structure of wood or similar material, including elongated substantially rectangular top and bottom walls 22 and 23 connected by flat rectangular end panels 24 and side panels 25. The joints between the walls and panels may

35 be sealed, as illustrated in Figure 6, by an overlapping strip 26. A plurality of the pontoons are suspended from the projecting ends of the beams 20 in longitudinal alignment with each other and in a manner to entirely encircle the hull.

An essentially thick layer of concrete 27 encloses the layer of rubber 19, which last-mentioned layer extends upwardly along the side walls of the hull to abuttingly engage the bottom wall 23 of the pontoons. In order that the concrete may be made more buoyant, I have provided a plurality of inflatable rubber tubes 28 which are imbedded in regular superposed rows in the layer 27. The tubes are of cylindrical formation and the opposite ends thereof are sealed by the transverse walls 29. Valves 30

carried by the end walls of the tube permit air under pressure to be introduced therein, and a plurality of tubes are concatenated in longitudinal alignment by the couplings 60, whereby the connected tubes define a row which extends entirely around the hull. As best illustrated in Figure 7, the concatenated circlets or rows of tubes imbedded in the concrete are arranged in closely placed superposed relation with each other. The layer of concrete is, therefore, materially lightened by the honeycombing effect of the multiplicity of tubes imbedded therein and the buoyancy of the layer is increased by the presence of air or other gas within the tubes.

Superimposed layers of soft rubber 31 and elastic rubber 32 thereafter successively enclose the hereinabove-described layers. The soft rubber layer 31 extends upwardly along the sides of the hull and outwardly around the projecting outer side walls 25 of the pontoons to terminate flush with the upper wall 22 thereof. The layer of elastic rubber 32 similarly extends upwardly along the sides of the hull and outwardly around the portion of the layer of soft rubber enclosing the pontoons 21. The layer 32, however, extends above the pontoons and the upper marginal edge 33 thereof is bent inwardly to abuttingly engage the ends of the steel beams 20.

The outer surface of the layer 32 is provided with longitudinally extending strips 34 of sponge rubber which pass entirely around the hull and in substantially vertically spaced relation with each other to provide a plurality of air chambers 35 therebetween. The strips extend upwardly along the sides of the hull to substantially the water line and are replaced above the water line by a solid layer 36 of sponge rubber, the upper marginal edge of which last-mentioned layer follows the contour of the outwardly projecting portions of the layers 31 and 32. A layer of elastic rubber 37 is next superimposed on the strips 34 and layer 36 to entirely close or seal the air chambers 35. The upper marginal edges of the layer 37 similarly project outwardly and around the upper margin of the layer 36 and the edge 38 thereof is turned inwardly over the edge of the layer 36 to abuttingly engage the outer surface of the layer 32. The rubber strips 34 permit a certain desirable yieldability or resiliency between the layers 32 and 37 and the air chambers therebetween materially increase the buoyancy of the hull.

Upon the elastic rubber layer 37 I have provided a layer of asbestos 39, and the layer of asbestos is in turn covered by a thin metallic sheet material 40 of aluminum, or the like. The outer metallic layer lends a pleasing appearance to the hull and provides an essentially rigid shell which holds the inner and softer layers fixedly in place. The upper edges of the layers 31, 32, 36, 37, 39 and 40 which extend around the pontoons 21 form a gunwale or bumper 41 which projects from the surface of the hull to prevent the same from being battered or damaged when lying along side a pier or dock, or when a collision occurs between ships or between a ship and a floating object. The asbestos layer 39 disposed directly within the outer shell 40 is adapted to prevent the inflammable inner rubber layers from being set afire in the event that the hull is torpedoed or that the decks or other inflammable parts should be set in flames as a result of the explosion.

A double layer of pontoons 21 are suspended from the portions of the steel beams 20 extending

between the side walls of the hull, as clearly illustrated in Figure 7, and the layers of pontoons are separated by a sheet of cork 42. A plurality of transversely extending wooden beams 43 are disposed in supporting relation below the bottom layer of pontoons and the opposite ends thereof are supported by angle braces 44. The upper beams 20 and the lower beams 43 hold the pontoons firmly in place and tightly packed to prevent inadvertent or accidental displacement of the individual pontoons in each layer. The pontoons entirely close the hull and a layer of concrete 45 covers the steel beams 20 to provide a floor for the lower deck of the vessel.

15 The space 46 below the wooden beams 43 comprises the hold of the vessel, which hold is lined with superimposed layers of materials in the following manner. The inner surface of the steel hull 11 is lined with a layer of cork 47 and the 20 inner surface of the cork layer is lined with a layer of hard rubber 48. The innermost layer 25 comprises a concrete shell 49 having a plurality of vertically spaced rows of inflatable rubber tubes 28 imbedded therein. The tubes comprising each row are connected in the same manner as the rows of tubes contained by the outer concrete layer 27. A sheet of asbestos 50 is preferably secured to the undersides of the wooden beam 43 to finish the hold and to provide an 30 entirely fireproof enclosure.

The portion of the sides 12 and 13 of the hull which extends above the concrete floor 45 is traversed by the upper deck floor beams 51 the ends of which are supported by angle braces 52. 35 The ends of the beams extend through the sides of the hull and the projecting ends are supported by vertical braces 53. The vertical braces 53 and the extending ends of the upper deck floor beams are suitably connected, as by the angle 40 clips 54, and provide an outer promenade deck. The bottoms of the beams 51 are covered by a layer of asbestos 55 and vertically spaced layers of closely packed pontoons 21 are disposed thereon. A layer of cork 56 is interposed between the 45 layers of pontoons and the steel beams 57 extending between the side walls of the hull 11 above the pontoons hold the same in fixed association with each other. A layer of concrete 58 covers the steel beams 57 and provides a floor for the upper deck. Pontoons 21 are also arranged 50 exteriorly of the sides of the hull, in the manner illustrated in Figure 7, which last-mentioned pontoons are enclosed by an outer fireproofing layer of steel or concrete 59.

55 Each of the layers comprising the hull may be separated by a plurality of sheets of Cellophane, or like material, which sheets are essentially strong and flexible and serve to hold the individual layers in proper association with each other.

60 The unique formation and composition of the several layers which surround the hull of the vessel provide an essentially thick and resistant armor therefor. The superimposed layers of 65 hard and soft rubber permit the armor to yield under a severe impact but, at the same time, present a tough and substantially unpenetrable barrier for a shell or torpedo. A shell or torpedo does the greatest damage when it strikes a solid and unyielding object such as the eighteen inch wall of solid steel which now comprises the hull of most large vessels. If the hull is enclosed by a plurality of inherently yieldable and resilient layers which absorb the shock of the 70 shell or torpedo, the damage to the hull is mate- 75

rially lessened. The various layers enclosing the hull may be applied directly to the hull when the vessel is constructed or they may be easily and expeditiously added thereto after the vessel is finished. The layers of armor may even be applied to a ship's hull after the same has had several years of active service. The myriad of air chambers 35 disposed near the outer surface of the armor will materially increase the buoyancy of the hull even in the event that the same is penetrated by a shell and the inner layer 27 of concrete will offer further and substantial resistance to a shell. The manner in which the layer of concrete is honeycombed with inflatable tubes 28 will aid in preventing the hull from sinking even though entirely penetrated by a shell. The inner layer of concrete 49 serves the same purpose as the outer layer 27.

In the event that the hull and protective armor should be penetrated and substantial quantities of water permitted to enter the hold 46, the double layer of pontoons interposed between the steel and wooden beams 20 and 43 will afford sufficient buoyancy to prevent the hull from sinking entirely below the surface of the water. The manner in which the pontoons are entirely enclosed by fireproof material will substantially limit the possibility of their being destroyed by fire. The pontoons below the upper deck, i. e., those interposed between the steel and wooden beams 57 and 51 further add to the buoyancy of the hull in the event that the vessel is shelled and becomes swamped.

It is to be understood, that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. In a ship having a metallic hull forming a shell, a layer of cork applied to the interior and the exterior of the said shell, a layer of hard rubber covering each cork layer, a layer of concrete applied to cover each of the said hard rubber layers, a covering of yielding and elastic rubber applied to the exterior layer of concrete, and a metallic shell covering the yielding rubber.
2. In a ship hull construction, an inner metal shell, a layer of cork applied to the exterior of the said shell, a layer of hard rubber covering the said cork, a layer of concrete having air containing cells applied over the hard rubber, a layer of yielding rubber covering the said concrete layer, a layer of elastic rubber applied over the yielding rubber, a plurality of spaced strips of yielding and resilient material disposed in spaced relation against the exterior of the elastic rubber, a covering of resilient rubber applied over the said elastic strips and forming air chambers between the said strips, and an exterior metal shell covering the said outer layer of resilient rubber.

ISIDORE ZUCKERMANN.
